UNITED STATES PATENT OFFICE.

WINGATE S. THOMAS, OF CHICAGO, ILLINOIS, ASSIGNOR TO KNAPP BROTHERS MANUFACTURING COMPANY, OF CHICAGO, ILLINOIS, A CORPORATION OF ILLINOIS.

ATTACHING MEANS FOR BUILDING TRIMS.

Application filed August 14, 1926. Serial No. 129,160.

In modern building construction, it is quite common, especially in hotels or the like, to employ metal trim, such as window sills, base boards, door and window casings, etc., and in the use of such metallic trim means must be provided for firmly and rigidly securing the trim in position. In these circumstances it is customary to secure such trim by clips nailed on wooden inserts, blocks, or studdings, which, however, are irregularly spaced so that provision must be made for locating the clips in whatsoever position attachment is afforded.

The present invention is designed to provide on the edge of the base board plate, or other trim, to which the invention is applied, an attaching flange so conformed and configured as to afford a sliding connection for a plurality of clips which may be thus slid along to the desired position, and thereafter firmly and rigidly clamped to the flange in such a way as to prevent any further movement between the flange and clip. This meets the requirement for permitting the clips to be suitably located to register with the joists, blocks, or other wooden inserts.

In the drawing:

Figure 1 is a sectional view of a metallic base board plate showing the attaching clips applied to the upper and lower edges;

Fig. 2 is a sectional elevation of the upper edge of such a base board plate showing the clip as initially applied thereto;

Fig. 3 is a similar view showing the clip clamped to the edge;

Fig. 4 is a perspective view of a section of the base board plate showing the clip in position; and

Fig. 5 is a section of a window sill or the like having the invention applied thereto.

Two applications of the invention are shown for purposes of illustration, but it will, of course, be understood that the invention is equally applicable to other forms of metallic building trim which provide an edge which may be flanged and attached in a manner hereinafter to be described.

The invention is shown as applied to a base board plate 10, the lower edge 11 of which is rounded inwardly to afford a cove 12 which is desirable for sanitary reasons. The upper and lower edges of the base board plate are both provided with the attaching features of the present invention, so that description of one will suffice for both.

Each edge, at the point which marks the limit of the exposed portion of the trim, is turned backwardly upon itself to afford a groove or channel 13. The free edge of the inner section 14 is in turn bent inwardly at 60 right angles to afford a marginal flange 15 which, it will be noted, extends inwardly at substantially right angles to the exposed surface of the base board plate or the like, and at a short distance below the turned 65 over edge thereof.

The marginal flange 15 may be termed a clamping flange, and this co-operates with a series of clips 16, each clip comprising an attaching plate 17 adapted to abut against a 70 wooden block, insert, studding, or the like, 18, to which the clip is secured by means of a nail 19 driven through a hole 20 in the attaching plate portion of the clip. The clip comprises an outstanding base flange 21 75 which terminates in a marginal rim flange 22 which, as shown, lies in a plane slightly divergent to the plane of the attaching plate portion of the clip, and extends into the channel 13 formed under the turned-over 80 edge of the base board plate. Each of the clips is provided with an upstanding tongue 23 which is struck upwardly from the metal of the flange 15 and initially stands in a position to lie closely adjacent to the free inner 85 edge of the flange 15, but out of gripping contact therewith.

The arrangement is one which initially permits the clips to be removed freely along the edge of the base board plate until 90 brought into position for attachment, after which the tongues are struck downwardly to engage and clamp over the edge of the flange 15, as best indicated in Fig. 3. This striking down and clamping of the tongues 95 slightly tilts or cant the clip and causes the rim flange 22 thereof to bind or clamp against the walls of the channel, as shown in Fig. 3, thereby tightly clamping the parts together in such a manner as to prevent any 100 movement.

The arrangement is one which permits a loose initial fit of the parts and ensures a tight rigid ultimate fit despite slight variations in the width of the channel, and is 105 otherwise much superior to an arrangement in which an effort is made to secure a close fit between the channel and the edge of the clip, which fit, if sufficiently close and tight to prevent ultimate movement of the parts, 110

will also prevent an easy adjustment of the clips to the desired positions.

The formation of the clip, with its outstanding base flange 21, serves to space the base board plate, or other trim, away from the wall structure a distance substantially equal to the width of the base flange. This arrangement serves to hold the base board plate in position to permit the plaster surface to be built up to lie flush therewith. Furthermore, the spaced arrangement of the clips affords openings between the same in which a grouting of mortar may be poured to fill in the space behind the base board plate after the same has been positioned. In like manner the lower edge of the base board plate is secured to the floor, and in this instance an offset is afforded which permits the cement floor to be built up to a level with the inturned portion of the base board plate, or to a slight level below the same, in case a linoleum floor surface is to be provided.

The method of securing the edge of a window sill or the like is precisely similar to that heretofore described, as indicated by inspection of the window sill 24 shown in Fig. 5. Other forms of trim which are similarly provided with backwardly turned portions to afford a channel terminating in a clamping flange may be likewise attached by clips of the character described, so that further illustration of the applicability of the present invention to various forms of trim is not deemed necessary.

In use, the base board plate, or other trim, will be positioned in place, and the loosely mounted clips will be moved along to the required positions to register with the exposed wooden inserts adapted for nailing, after which the clamping tongues will be pressed down by the action of pliers, or other suitable tools, which clamping action will serve to tilt forward or cant the clips to bring the attaching plate portion 17 thereof in substantial parallelism with the plane of the wooden attaching surface which, as before noted, will serve to bring the marginal clamping flange 22 into angularly gripping relation to the walls of the channel, so that, when the clips are nailed in position in flatwise relation against the wooden attaching surface, the base board plate, or other trim, will be held rigidly against any vibration or movement. When the parts are thus positioned, the wall can be finished and the space behind the trim can be grouted, if desired.

The invention is one which is extremely easy to manufacture and which is convenient and efficient in use, since provision is made for actual clamping or biting contact between the clips and the channel walls, which method of securement is far superior to any with which I am familiar.

I claim:

1. In attaching means of the class described, the combination of a trim having a channel formed in its attaching portion and an inwardly turned flange along the margin 70 of said channel, a clip having a portion thereof entered into said channel, and a portion thereof formed to engage the inwardly turned flange, and means for attaching the clip, substantially as described. 75

2. In attaching means of the class described, the combination of a trim having a channel formed in its attaching portion and an inwardly turned flange along the margin of said channel, a clip having a portion 80 thereof entered into said channel, and a portion thereof formed to engage the inwardly turned flange, and means for attaching the clip, the relation of the parts being such that when the clip is attached, the portion thereof entering the channel will be tilted to clamp against opposite walls of the channel, substantially as described. 85

3. In attaching means of the class described, the combination of a trim having a 90 channel formed thereon and an inwardly turned flange extending along the edge of the channel, a clip provided along one edge with a portion entered into the channel and further provided with a tongue adjacent 95 the flange and adapted to be brought into clamping relation therewith, and means for attaching the clip, substantially as described.

4. In attaching means of the class described, the combination of a trim having a channel formed thereon and an inwardly turned flange extending along the edge of the channel, a clip provided along one edge with a portion entered into the channel and further provided with a tongue adjacent the flange and adapted to be brought into clamping relation therewith, means for attaching the clip, said means including a portion of the clip adapted to abut in flatwise 100 relation against a portion of the wall, and means entered through said clip portion and into the wall, substantially as described. 105

5. In attaching means of the class described, the combination of a trim having a channel formed thereon and an inwardly turned flange extending along the edge of the channel, a clip provided along one edge with a portion entered into the channel and further provided with a tongue adjacent 115 the flange and adapted to be brought into clamping relation therewith, and means for attaching the clip, the relation of the clip and channel being such that when the clip is attached to the wall, the portion thereof 120 entering the channel will be tilted to engage the opposite wall surfaces thereof, substantially as described. 125

6. In attaching means of the class described, the combination of a trim having a channel 130

formed thereon and an inwardly turned flange extending along the edge of the channel, a clip provided along one edge with a portion entered into the channel and further 5 provided with a tongue adjacent the flange and adapted to be brought into clamping relation therewith, means for attaching the clip, said means including a portion of the clip adapted to abut in flatwise relation 10 against a portion of the wall, and means entered through said clip portion and into the wall, the relation of the clip and channel being such that when the clip is attached to the wall, the portion thereof entering the 15 channel will be tilted to engage the opposite wall surfaces thereof, substantially as described.

7. In attaching means of the class described, the combination of a metallic trim 20 provided along its edge with a backwardly turned portion affording a channel, the edge of said portion being turned away from the trim to afford an attaching flange, a clip of L-shaped formation having its marginal 25 portion entered into the channel, its base portion underlying the flange, and the wall attaching portion outstanding from the trim in offset relation thereto and in position to abut flatwise against a portion of the wall, 30 and a tongue struck away from the base portion of the clip in position, when struck down, to embrace and clamp the channel flange between the tongue and the base of 35 the clip, the relation of the attaching portion of the clip and the marginal portion of the trim being such that when the tongue is struck down and the clip is attached to the wall, the marginal portion of the clip will 40 stand in oblique relation to and impinge 45 against the opposite walls, substantially as described.

8. In attaching means of the class described, the combination of a trim having 50 a channel formed in its attaching portion, a clip having a portion thereof entered into said channel, and means for clamping the clip to the trim in such a way that when the clip is attached, the portion thereof entering the channel will be tilted to clamp 55 against opposite walls of the channel, substantially as described.

35 8. In attaching means of the class de-

scribed, the combination of a metallic trim provided along its edge with a backwardly turned portion affording a channel, the edge of said portion being turned away from the trim to afford an attaching flange, a clip of L-shaped formation having its marginal portion entered into the channel, its base portion underlying the flange, and the wall attaching portion outstanding from the trim in offset relation thereto and in position to abut flatwise against a portion of the wall, and a tongue struck away from the base portion of the clip in position, when struck down, to embrace and clamp the channel flange between the tongue and the base of the clip, the relation of the attaching portion of the clip and the marginal portion of the trim being such that when the tongue is struck down and the clip is attached to the wall, the marginal portion of the clip will stand in oblique relation to and impinge against the opposite walls, substantially as described.

9. In attaching means of the class described, the combination of a trim having a channel formed in its attaching portion, a clip having a portion thereof entered into said channel, and means for clamping the clip to the trim in such a way that when the clip is attached, the portion thereof entering the channel will be tilted to clamp against opposite walls of the channel, substantially as described.
